DESIGN FOR A SPOON OR OTHER ARTICLE OF FLATWARE

Edward J. Conroy, New Haven, Conn., assignor to International Silver Company, Meriden,
Conn., a corporation of New Jersey

Application January 8, 1938, Serial No. 74,159

Term of patent 14 years

To all whom it may concern:

Be it known that I, Edward J. Conroy, a citizen of the United States, residing at New Haven, county of New Haven, State of Connecticut, have invented a new, original, and ornamental Design for a Spoon or Other Article of Flatware, of which the following is a specification, reference being had to the accompanying drawing, forming a part thereof.

Fig. 1 is a front elevation of a spoon showing my new design;

Fig. 2 is a sectional view taken on the lines 2—2 of Fig. 1; and

Fig. 3 is a sectional view taken on the lines 3—3 of Fig. 1.

The back of the spoon conforms with the disclosure of Figs. 2 and 3, and may be plain or have surface ornamentation embodying the motif disclosed in Fig. 1.

The design is intended for use on sets comprising spoons, forks, knives and similar articles of table-ware.

I claim:

The ornamental design for a spoon or other article of flatware, substantially as shown and described.

EDWARD J. CONROY.
